UNITED STATES PATENT OFFICE.

PATRICK H. MAHONEY, OF CHICAGO, ILLINOIS.

GASKET FOR HANDHOLE PLATES FOR WATER-TUBE BOILERS.

1,424,930.

Specification of Letters Patent. Patented Aug. 8, 1922.

Application filed May 3, 1919. Serial No. 294,531.

To all whom it may concern:

Be it known that I, PATRICK H. MAHONEY, a citizen of the United States, and a resident of the city of Chicago, county of Cook, 5 and State of Illinois, have invented certain new and useful Improvements in Gaskets for Handhole Plates for Water-Tube Boilers, of which the following is a specification.

10 My invention relates to improvements in gaskets for hand-hole plates for water tube boilers, and has for its object the provision of a metal gasket for hand-hole plates which will be durable, economical and efficient in 15 use.

A further object is to provide a gasket for a hand-hole plate which will be adapted to be easily and quickly removed or put into use.

20 Other objects will appear hereinafter.

The invention consists in the combinations and arrangements of parts hereinafter described and claimed.

The invention will be best understood by 25 reference to the accompanying drawings forming a part of this specification, and in which,

Fig. 1, is a plan view of a hand-hole on a water tube boiler,

30 Fig. 2, is a fragmentary section of a water tube boiler embodying the invention,

Fig. 3, is a perspective view of the invention, and

Fig. 4, represents a vertical sectional view 35 of Fig. 3.

To afford means of cleaning the water tube boilers, hand-holes 14 are provided in the front wall 5 of the water chamber 6. The purpose of these holes is to give access 40 to the water tubes 7 so that the same may be cleaned and have the coating, which accumulates on the inside thereof, scraped or removed therefrom. To close these hand-holes in the wall 5, are provided what are popu-

45 larly termed as hand-hole plates 8, from which vertically project threaded studs 9. In placing the hand-hole plate 8 into operative position, it is inserted into the water chamber 6 of the water tube boiler, with the

50 shoulders of the hand hole plate engaging the wall 5 of the boiler. Interposed between the hand-hole plate 8 and the wall 5 is a gasket 10. Co-operating with the hand-hole plate is a closing plate 11 positioned against the wall 5 of the boiler on the opposite face to which the hand-hole

plate is placed. The stud 9 projects through the plate 11, and co-operating therewith is a nut 12, by means of which the different parts are securely clamped in position. 60

Many different types of water tube boilers are in existence, and also many different types of hand-hole plates, but the hand-hole plate which is now used most universally with water tube boilers is what is known as 65

the Phoenix hand-hole plate. Where the Phoenix hand-hole plate is to be used, the hole 14 in the front wall 5 of the boiler is constructed substantially circular with two bulging portions diametrically opposite each other, as clearly seen in Fig. 1. 70

The reason for this is because the hand-hole plate is constructed substantially circular, having two bulging portions diametrically arranged opposite each other, said gaskets 75

being turned slightly inwardly at points where the bulged portions begin, to afford sharp edges at said points. The plate is, of course, larger than the hole with which it is used, but when the plate is turned so 80

that the center of the circular part of the plate is opposite the bulging part of the hole, the plate can then be easily removed by sliding one of the bulging ends of the plate through the hole. This particular 85

form of structure in the hand-hole plate is consequently seen to be an advantageous and useful feature of the hand-hole plate, inasmuch as each hand-hole plate can be 90

removed separately and separately supplied with a new one, in case of necessity, without disturbing any of the other hand-hole plates. If it were not possible to insert the hand-hole plate through the hand-hole, all of the hand-hole plates in this row would 95

have to be removed to allow passing of the hand-hole plates up from the base of the

water tube chamber to the point at which it is to be used.

Heretofore, circular gaskets formed of 100 rubber or asbestos have been used with these Phoenix hand-hole plates, but because of the structure of the hand-hole plate, these gaskets have proved unsatisfactory, inasmuch as the continuous close engagement 105

around the edge or flange of the hand-hole plate is not accomplished by the use of such gaskets. The result was that the water tube boiler leaked where these hand-hole plates were positioned, resulting in a corroding of 110 the stud 9. This occasioned frequent removal of the hand-hole plates, and, because

of the corroded condition of said hand-hole plates, the studs 9 were quite frequently twisted off said hand-hole plates. To overcome this difficulty, applicant has provided 5 a metallic gasket, preferably constructed of lead, which is so formed as to fit snugly and securely around the entire periphery or flange of the Phoenix hand-hole plate. With the use of this metal gasket, a hand-hole 10 plate can be removed, the gasket taken off, a new gasket put on and the plate immediately secured in its operative position without any need of scraping or cleaning of 15 said plate, as is necessary where a rubber or asbestos gasket is used.

Located on both sides of applicant's 20 gasket, extending circumferentially around the gasket, is provided a raised ridge. Upon the clamping of the hand-hole plate into position, this ridge will flow and fill up any 25 discrepancies which may exist between the surface of the gasket and the surface of the hand-hole plate and the chamber wall, thereby assuring a close and intimate contact.

25 While I have illustrated and described the preferred form of construction for carrying my invention into effect, this is capable of variation and modification without departing from the spirit of the invention. I, 30 therefore, do not wish to be limited to the precise details of construction set forth, but desire to avail myself of such variations and modifications as come within the scope of the appended claims.

35 Having described my invention, what I

claim as new and desire to secure by Letters Patent is:—

1. A lead gasket for a hand-hole plate, 40 said gasket being substantially circular in form and outwardly bulged at diametrically opposite points, said gasket having a circumferentially extending ridge located on both sides, substantially as described.

2. A metal gasket for a hand-hole plate, 45 said gasket being substantially circular in form and outwardly bulged at diametrically opposite points, said gasket being turned slightly inwardly at the points where said bulged portions begin, to afford sharp edges at said point, said gasket having a circumferentially extending ridge located on both sides, substantially as described.

3. A lead gasket for a hand hole plate, 55 said gasket being substantially circular in form and outwardly bulged at diametrically opposite points, said gasket being turned slightly inwardly where said bulged portions begin, to afford sharp edges at said points, said gasket having a circumferentially extending ridge located on both sides 60 and provided with bulged portions which correspond with the bulged portions of the gasket, substantially as described.

In testimony whereof I have signed my name to this specification in the presence of 65 two subscribing witnesses.

PATRICK H. MAHONEY.
